UNITED STATES PATENT OFFICE.

JOAQUIN ELEIZEGUI, OF NEW YORK, N. Y.

STENOTYPE-MACHINE.

1,202,686.

Specification of Letters Patent. Patented Oct. 24, 1916.

Application filed July 16, 1914. Serial No. 851,376.

To all whom it may concern:

Be it known that I, JOAQUIN ELEIZEGUI, a citizen of Cuba, and a resident of the city of New York, borough of Manhattan, in the county and State of New York, have invented a new and Improved Stenotype-Machine, of which the following is a full, clear, and exact description.

My invention relates to stenotype machines, and an object thereof is to provide a simple, strong and inexpensive machine which is ribbonless and substantially noiseless.

Another object of the invention is to provide a machine of the class described the impression of which can be understood by any one having the key or a knowledge of the relative combinations of the impressions.

A further object of the invention is to provide a machine of the class described which can be used for producing impressions on ordinary paper, to be read with a code; or it may be used with paper provided with the code.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views, and Figure 1 is a plan view of an embodiment of my invention; Fig. 2 is a longitudinal section thereof; Fig. 3 is a plan view of the impressed paper and the code; Fig. 4 is a plan view showing the impression left by the machine on a paper provided with the code; and Fig. 5 is a plan view of a modified design of the paper to be used in connection with my machine.

Before proceeding to a more detailed description of my invention, it must be clearly understood that the foundation of my stenographic system lies in the writing of the consonants according to their sounds and eliminating the vowels. As, for example, health is written h l th. It must be further noticed that as many letters of a word as is possible, owing to their position in the code, will be written on each line; and in case the word cannot be finished in one line, the remaining letters will be indicated in the following, *i. e.*, the second and may be the third and further lines, according to the

number of duplicate letters in the word, and also according to the position of the letters on the keyboard of the machine. As, for example, to write purpose the letters would be located as follows:

p r
p s.

Patrimonial would be written:

p t r
m n

1

This simple system of taking notes will enable the operator to take notes of letters, speeches, etc., very rapidly, as the simplicity of the system is self-evident, both for writing and for translating the notes. However, to further facilitate the translation of notes, the operator may use the vowels at any time he should deem it advisable to do so. As, for example, above may be written:

a
b f.

80

Drama may be written:

d ra
m a.

In order to reduce the number of lines that a word would otherwise occupy, certain combinations of letters to represent certain sounds may be used. For example, "action" may be represented by the vowels ai.

Referring to the drawings, 6 represents the frame of the machine between the sides of which a round bar 7 is provided to form the axis or pivot for the keys 8. Positioned between the sides of the frame 6 is a second bar 9, above the bar 7 and substantially in alinement therewith, which bar forms the pivot for the punching bars 10. Each of the bars 10 is pivotally connected at its lower end to a corresponding key 8 by means of a pin 11. The upper end of the punching bar is provided with a needle 12 which faces an aperture 13 provided in the paper guide 14 secured to the top 15 of the frame.

It will be noted from Fig. 1 that all of the punching bars 10 are in an alining position between the sides of the frame 6, and that the first key in the first row is connected to the first punching bar, and the last key in the last row is connected to the last punching bar. The intermediate keys, as can be seen, are connected to the consecutive punching bars, *i. e.*, the last key of the first

- row being connected to the tenth punching bar, and the first key of the second row to the eleventh punching bar, etc. By depressing any of the keys in the keyboard, the corresponding punching bar is moved on its pivot, so that the needle 12 of the bar is moved toward the paper guide 14. The punching bar and key are restored to their normal position by resilient members 15'.
 10 The keys are maintained in the normal position by the provision of a bar 16 engaged between the sides of the frame 6, which forms a stop for the punching bars 10.
 15 The keyboard in my machine contains twenty-two keys; and from the first to the last the following letters are represented by the successive keys:

20 h w k d p b m s g t
 f.v l n j r a e i o u
 y.th ch.sh

The numerals are represented in the following fashion: 1 is represented by the letter 25 w; 2, by the letter k; 3, by the letter d, etc.; 9 being represented by the letter t. The zero 30 is represented by the vowel o. In order to know when these characters represent figures, the letter h will be used at the beginning and the letters th at the end of each figure. As, for example, 561 will be written:

h b m.
 w th

- 35 The paper to be impressed is carried in the rear part of the machine. A suitable axle 16' engaged between the sides of the machine forms the support for the roll of paper 17, the paper from the roll passing 40 over the paper guide 14 to a feed roll 18. The paper is maintained taut on the guide 14 by the engagement of the paper on the feed roll 18 by a pressure roller 19, the rollers 18 and 19 being mounted in a frame 45 20 secured to the top 15 of the frame 6. The part of the frame 20 carrying the roller 19 is hinged to the major part of the frame 20; and suitable means are provided to maintain the roller 19 against the roller 18.
 50 The feed roll 18 is provided with a ratchet 21 which is adapted to be engaged by a pawl 22 carried by an arm 23 mounted to swing on the axle of the feed roller 18. The engagement between the pawl and the 55 ratchet is maintained by the action of gravity on the pawl. The arm 23 is connected by a link 24 to one side of a swinging frame 25. The frame 25 is U shaped, having its ends pivotally connected to the sides 60 of the frame 6, as shown at 26, while the bottom 27 of the U frame 25 rests against the lower edge of the keys 8 (see Fig. 2). When any of the keys is depressed the frame 25 is made to swing, thus displacing the arm 65 23. The return movement of the frame 25

is obtained by a resilient member 28, and which return movement of the frame causes the rotation of the feed roller. The frame 20, at the top thereof, is provided with a bridging member 27', which serves as a 70 knife for severing the paper 28' from the roll.

It is evident that the perforations in the paper formed by the needle 12 of the punching bar are all the same and are identified 75 according to their relative positions. The translation of the perforations can be made according to the following method:

First: On a transparent body, such as glass, celluloid, mica, etc., is formed the 80 series of letters represented by the alining needle and in the same order, *i. e.*

h w k d p b m s g t
 fv l n j r a e i o u
 y.th ch.sh

85

And under this code the paper containing the perforations will be placed. This is illustrated in Fig. 3. The operator will then note that the perforations coincide or 90 are in alinement with the letters of the code; and these perforations will indicate that the letters alining or coinciding with them are the letters that the writer sought to use at the time of taking his notes. For instance, 95 if the translator should note that there is a perforation under k, under p and under t, these three letters are the ones that the writer wanted to use at the time of writing the word "kept." Second: A roll of paper 100 is provided on which the series of letters appear in the same order as on the keyboard. See Fig. 4. The perforations made on this paper will indicate directly the letters that the operator sought to use at the time of 105 writing. It is self-evident that in this second method the distance between the rows of letters can be made wider than the successive lines formed by the perforations on the machine; but, preferably, the rows of 110 letters on the paper are the same distance apart as the distance between the rows of perforations formed by the machine. Third: A roll of paper may be provided on which are longitudinal lines 30. These lines 115 are properly spaced so that the line *c* represents the place of the letter *h* on the keyboard; line *g*, the letter *p*; line *v*, the letter *t*; line *x*, the letter *a*; line *y*, the character *ch*. Any perforations located between these 120 lines can be easily determined, knowing the characters which are supposed to be located between the said lines.

The advantages of my machine are that the writing is obtained without the use of 125 a ribbon; there are fewer parts in the machine; there is less danger of the machine getting out of order; there is less hammering on the paper, as less force is required to perforate the paper than to print thereon. 130

From the foregoing description, taken in connection with the accompanying drawings, the advantage of the construction and operation of the device shown will be readily understood by those skilled in the art to which the invention pertains; and while I have described the principle of operation, together with the device which I now consider to be the best embodiment thereof, I desire to have it understood that the device shown is merely illustrative and that such changes may be made when desired as are within the scope of the appended claims.

Having thus described my invention, I claim as new and desire to secure by Letters Patent:

1. In a stenotype machine, a main frame, a plurality of keys having angular inner ends, bars pivoted intermediate of their ends and each having one end pivoted to the angular inner end of a key and carrying at its other end means for producing an impression, a guide opposite the impression means and over which the paper passes, a pivoted and spring pressed U-shaped frame having its free end extending under the angular ends of the keys, a paper carrying roller mounted in the main frame, and a feed mechanism for feeding the paper from the roller over said guide, and a connection between the feed mechanism and the pivoted frame.

2. In a stenotype machine, a main frame, a plurality of keys, a pivoted and spring pressed U-shaped frame having its free end extending under the keys, a paper carrying roller mounted in the main frame, a guide over which the paper passes, a paper feed roller, a pawl and ratchet mechanism for operating the feed roller, means whereby the pawl and ratchet mechanism will be operated by said pivoted frame, and impression devices opposite the guide and operatively connected with the keys. 35

3. In a stenotype machine, a main frame, a plurality of keys, a pivoted and spring pressed frame having its free end extending under the keys, a paper carrying roller mounted in the main frame, a guide over which the paper passes, rollers for feeding the paper, a ratchet wheel carried by one roller, an arm loosely mounted on the axle of the roller carrying the ratchet wheel, a pawl carried by said arm, and engaging 50 the ratchet wheel, a link connecting the arm with the pivoted frame, and impression carrying members operated by the keys. 45

In testimony whereof I have signed my name to this specification in the presence of 60 two subscribing witnesses.

JOAQUIN ELEIZEGUI.
